US00D843887S

(12) **United States Design Patent** (10) **Patent No.:** **US D843,887 S**
(45) **Date of Patent:** **** Mar. 26, 2019**

(54) **D-RING**

- (71) Applicant: **Ossur Iceland ehf**, Reykjavik (IS)
(72) Inventors: **Lindsay Frost**, Foothill Ranch, CA (US); **Jared Olivo**, Foothill Ranch, CA (US)
(73) Assignee: **OSSUR ICELAND EHF**, Reykjavik (IS)

(**) Term: **15 Years**

(21) Appl. No.: **29/636,626**

(22) Filed: **Feb. 9, 2018**

Related U.S. Application Data

- (62) Division of application No. 29/583,652, filed on Nov. 8, 2016, now Pat. No. Des. 813,089.

CLAIM

The ornamental design for a D-ring, as shown and described.

DESCRIPTION

FIG. 1 is a perspective view of a D-ring.

FIG. 2 is a first side elevational view of the D-ring in FIG. 1.

FIG. 3 is a second side elevational view of the D-ring in FIG. 1.

FIG. 4 is a top plan view of the D-ring in FIG. 1.

FIG. 5 is a bottom plan view of the D-ring in FIG. 1.

FIG. 6 is a front elevational view of the D-ring in FIG. 1; and,

FIG. 7 is a rear elevational view of the D-ring in FIG. 1. The broken lines illustrate environmental supplementary structure of the D-ring and form no part of the claimed design.

1 Claim, 2 Drawing Sheets
